MASSACHUSETTS.

CARBURETER.

1,183,452.

Specification of Letters Patent. Patented Mar. 30, 1915.

Application filed July 22, 1912. Serial No. 716,326.

To all whom it may concern:

Be it known that we, MILES E. BABBITT, a resident of Brookfield, and JAMES F. BEAUMONT, a resident of Worcester, in the county of Worcester and Commonwealth of Massachusetts, both citizens of the United States, have jointly invented a new and useful Improvement in Carbureters, of which the following is a specification, accompanied by drawings forming a part of the same.

Our invention relates to internal combustion engines and resides particularly in certain improvements in carbureters for this type of engine.

Our improved carbureter is designed mainly for use in connection with automobile engines using gasoline for fuel, although it is obvious that it may be used in connection with engines for driving other kinds of machines, or with those using some other fuel.

One object of our invention is to provide means for heating the gasoline or other fuel just prior to its being mixed with the air, and this feature we believe to be broadly new. There is a decided advantage in warming the fuel at this point in that it will cause the fuel to mix more thoroughly and quickly with the air as they come together, and the resulting mixture will be more easily ignited, both for the reasons just stated, and for the reason that the mixture is warmer than it would have been if the fuel had not been warmed as described.

Other objects and advantages of our invention will appear as the description proceeds.

In order to make our invention clear, we have shown in the accompanying drawings and in connection therewith will proceed to describe what we believe to be the most desirable form thereof, but obviously various changes may be made without departing from our invention as defined in the appended claim.

In the drawings, Figure 1 is a view in elevation of one form of our carbureter connected with a float chamber. Fig. 2 is a similar view except that the carbureter is shown in section, and Figs. 3, 4, 5 and 6 are face views of the valve plates used in automatically assisting in regulating the

flow of air into the air chamber, and from 55 there into the mixing chamber.

Similar reference characters refer to similar parts throughout the various figures.

The frame of the carbureter is in two parts, the lower part 1 containing the air chamber 2, and the upper part 3 containing the mixing chamber 4. A float chamber 5 is connected with the carbureter to supply fuel thereto. Any suitable float chamber may be used as it forms no part of the present invention, and a specific description of the chamber is therefore not necessary. As the fuel leaves the float chamber 5, it passes into a small chamber 6 from which a needle passage 7 carries the fuel on to the mixing chamber 4 where it comes into contact with the air and is mixed therewith. The chamber 6 has a thin wall 8 on the other side of which is a second chamber 9 containing a small resistance coil 10 held 75 in place by a thumb nut 11, which also serves as a cover for the chamber 9, so that the resistance coil 10 may be easily removed and replaced. The thumb nut 11 carries one of the conductors 12 from a suitable 80 source of electric current to the resistance coil 10, this conductor being insulated from the thumb nut by the insulating bushing 13. The other conductor 14 from the source of current is electrically and mechanically connected to the frame of the carbureter by the screw 15. The resistance coil 10 has one of its terminals connected to the conductor 12, as indicated in Fig. 2, and its other terminal is so located on the surface of the 85 coil that it is pressed firmly against the frame of the carbureter by the thumb nut 11, thus completing the circuit to the other conductor 14. The electric current passing through the resistance coil 10 generates 90 an amount of heat in the coil predetermined more or less accurately by the resistance of the coil used and the voltage of the battery or other source of current. This heat passes by conduction through the thin wall 8 to 100 the fuel in the chamber 6, thus warming the fuel at this point and keeping it warm until it passes to the mixing chamber. The advantages secured by warming the fuel at this point have already been stated. The 105

partial vacuum created in the cylinder or cylinders during each cycle causes a more or less violent rush of outside air through

the air intake opening 16 into the chamber 2, thence through an annular opening about the upper end of the needle passage 7 to the mixing chamber 4 where it is mixed with fuel, and finally past the throttle valve 17 to the manifold from which it is distributed to the various cylinders of the engine.

The purpose of the float tank 5, as is well known, is to keep the fuel at a proper level near the top of the needle passage 7, so that as the air rushes past the end of this needle passage a quantity of the fuel will be drawn out of the end of the passage by suction, converted into the form of a fine spray and thoroughly mixed with the air in the mixing chamber 4.

To regulate the size of the intake opening 16 in accordance with the temperature of the outside air, we provide a cap 18 of approximately the size of the upper end of the passage 19 leading to the air chamber 2 and adjustably separated from the end of such passage. The cap 18 is supported in its adjusted position by a cross bar 20 rigidly connected with the sides of the passage 19, this cross bar 20 carrying an upright threaded post 21 onto which the cap 18 is screwed, as shown. The cap is secured in any desired adjustment by a lock nut 22. By varying the adjustment of the cap 18 along the post 21, it is obvious that the size of the intake opening 16 is correspondingly varied, and the quantity of air admitted through this opening thereby regulated for the purposes already stated. We have found that under certain conditions, as when the speed of the engine is considerably above normal, the amount of air necessary cannot pass quickly enough through the opening 16, the size of which has been adjusted for normal or average conditions. We therefore provide for the further admission of air when required by providing the perforated plate 23 mounted in the wall of the air chamber 2. This plate has its periphery screw-threaded so as to fit to corresponding threads in the opening in which the plate is mounted. The plate 23 slidably supports one end of a short rod 24 passed through a hole in its center, the other end of the rod 24 being slidably held in a support 25 rigid with the frame of the carburetor. A second plate 26 is slidably mounted on the rod 24 and is held in contact with the inner face of the plate 23 by a spiral spring 27 surrounding the rod 24 and confined between the plate 26 and the stop 28 fixed to the rod 24. The plate 26 is unperforated except to accommodate the rod 24 through its center and is large enough to cover and close all the perforations in the plate 23. The two plates 23 and 26 are held together and the pressure between them is regulated by the thumb nut 29. The opening in the support 25 is polygonal and the

corresponding end of the rod 24 is similarly shaped in cross section so that the rod cannot turn and vary the position of the thumb nut 29 thereon. When the engine cylinders require air too fast to be properly supplied through the intake opening 16, it is obvious that a partial vacuum greater than normal will be created in the air chamber 2. With a proper adjustment of the thumb nut 29, however, the plate 26 will be moved against the pressure of the spring 27, when the difference in pressure between that of the outside air and that of the air in the air chamber 2 has reached a predetermined maximum. Automatically acting means is thus provided for limiting the vacuum in the air chamber 2 to a predetermined maximum and as a result it is assured that there will be a sufficient supply of air in the air chamber under all conditions even though the primary air intake is adjusted to normal conditions. We also find that under certain conditions, such as already referred to, air cannot pass quickly enough through the annular passage surrounding the upper end of the needle passage 7. To overcome this difficulty, we provide the perforated flat annular ring 30 threaded or otherwise suitably mounted in the opening between the air chamber 2 and the mixing chamber 4. Covering and closing the perforations in this annular ring 30 is a second flat annular ring 31 slidable on headed studs 32 rigidly mounted in the ring 30. The rings 30 and 31 are held yieldably in contact by the springs 33 confined between the movable ring 31 and the heads of the studs 32. The central openings in the rings 30 and 31 form the annular openings surrounding the upper end of the needle passage 7. Both of the rings 30 and 31 are perforated for the passage of air, but these perforations do not register and so when the rings are in contact no air can pass through the perforations. It is obvious that when the engine requires air faster than it can pass through the central openings of the rings 30 and 31, a difference in pressure between that in the mixing chamber 4 and that in the air chamber 2 will be created sufficient to overcome the pressure of the springs 33, the pressure of these springs against the ring 31 having been properly adjusted, of course, by turning the threaded studs 32. The difference in pressure between that in the mixing chamber 4 and that in the air chamber 2 is thus automatically limited to a predetermined maximum.

The usual throttle valve 17 is rotatably mounted in the passage between the mixing chamber 4 and the manifold for regulating the supply of fuel to the engine. The axis of the throttle valve is extended through the wall of the passage in which it is located and on the outer end of this axis is secured

a crank arm 34 which is adapted to be connected at its lower end with suitable controlling mechanism within reach of a person driving the engine. The crank arm 34 oscillates in a slot in a shelf or plate 35, the material at each end of the slot being turned up at an angle to form supports 36 for adjustable screws 37, which form stops to limit the oscillations of the crank arm 34, so that 5 at one extreme position of said crank arm the throttle valve will be closed and at the other extreme position, the throttle valve will be wide open.

10 We claim,
15 In a carburetor, the combination, with a

shell or casing having a fuel passage therein connecting the fuel supply means with a spray nozzle, of an exterior hollow boss on said casing adjacent said passage, there being a thin wall between said passage and 20 the interior of said boss, a resistance coil fitted within said boss in contact with said wall, and a detachable closure for said boss for maintaining said coil in position.
